UNITED STATES PATENT OFFICE.

HENRY WATERSTONE, OF MONTGOMERY, WEST VIRGINIA.

WRAPPING MACHINE.

Application filed July 24, 1922. Serial No. 577,122.

To all whom it may concern:

Be it known that I, HENRY WATERSTONE, a citizen of the United States, residing at Montgomery, in the county of Fayette and State of West Virginia, have invented certain new and useful Improvements in Wrapping Machines, of which the following is a specification.

This invention relates to wrapping machines for wrapping up articles of various sorts and has special reference to a wrapping machine particularly adapted for the wrapping of bread, cakes and other similar articles of loaf like form.

One important object of the invention is to improve and simplify the general construction of devices of this character.

A second important object of the invention is to provide an improved bread wrapping machine wherein the loaf will be automatically conveyed to the wrapping mechanism through a step by step movement, elevated for engagement by said wrapping mechanism, wrapped, sealed and delivered to a delivery conveyor without the intervention of the hands.

A third important object of the invention is to provide an improved paper feeding mechanism.

A fourth important object of the invention is to provide, in a machine of this character, an improved means for successively wrapping one side and the bottom of an article and tucking the ends of the wrap-

per in.

A fifth important object of the invention is to provide an improved means for moving the loaf or other article into engagement with wrapping devices to furnish the wrapping and at the same time to release the loaf for action by the conveyor.

With the above and other objects in view, the invention consists in general of certain novel details of construction and combinations of parts hereinafter fully described, illustrated in the accompanying drawings, and specifically claimed.

In the accompanying drawings, like characters of reference indicate like parts in the several views, and:

Figure 1 is a side elevation of the complete machine.

Figure 2 is a plan view of the machine with portions of the conveyor broken away in order to disclose on a larger scale the remainder of the machine.

Figure 3 is a longitudinal section on the line 3—3 of Figure 2.

Figure 4 is a transverse section on the line 4—4 of Figure 2.

Figure 5 is a detail view of a portion of the paper feeding mechanism.

Figure 6 is a detail view of a portion of a certain conveyor actuating mechanism.

Figure 7 is a detail of a portion of the feeding mechanism.

Figure 8 is a view showing the bread in position for the wrapping operation.

Figure 9 is a diagrammatical view showing the first steps in the wrapping operation.

Figure 10 is a similar view showing the second step in such wrapping operation.

Figure 11 shows the third step of the operation.

Figure 12 shows the fourth step.

Figure 13 shows the fifth step.

Figure 14 shows the completely wrapped loaf in position for sealing.

Figure 15 is a view of the paper cutting knives.

In the embodiment of the invention herein illustrated the same has been disclosed as adapted for the wrapping of the loaves of bread of various sizes but it is to be understood that the use of this machine is not confined to bread wrapping but it may be utilized for the wrapping of various other articles having the general form of a bread loaf. This invention is mounted on a main bed or frame 10 which is preferably cast as a unit and projecting from one side of this frame is a pair of arms 11 supporting the paper feeding mechanism. At the outer end of these arms there are formed suitable

bearings to receive the ends of a shaft 12 having paper roll supports 13 located thereon and movable to accommodate paper of different widths. The ends of the shaft 12 are held in position by means of bearing caps 14 which are attached at one end pivotally to the arms as at 15. The other end of each of these caps is slotted to receive a holding down bolt 16 having a nut 17 thereon between which and the cap is arranged a coil spring 18. In spaced relation to the shaft 12 there is journalled in the arms 11 a feeder shaft 19 and above the bearings for this shaft are slots 20 wherein are slidably mounted bearings 21 supporting a presser roll 22, these bearings being normally forced downward by means of a plunger 23 pass-

ing through a cap 24 secured to the arm 11 at each end of said shaft. By this means when the feed roll or shaft 19 is rotated the paper will be fed forward so long as the bearings 21 are forced downward. In order to raise these bearings and stop the feeding of the paper there is provided at the top of each of the plungers an eye or loop 25 and through these eyes passes a lift bar 26 pivotally connected at each of its ends to an angularly lift link 27. On one of the links 27 is a handle 28. As shown in Figure 1, movement of the handle 28 toward the right of that figure will cause lifting of the bar 26, consequently releasing the pressure on the paper. In order to actuate the feed roll 19 there is provided on one end of its shaft a bevel gear 29 wherewith meshes a bevel gear 30 fixed on a shaft 31 extending at right angles to the feed roll. On this shaft 31 is fixed a ratchet 32, and rotatable on the feed shaft adjacent said ratchet is a gear wheel 33 carrying pawls 34 which engage with the ratchet. Meshing with the gear 33 is a rack bar 35 which is slidable longitudinally of the machine and is connected by a link or connecting rod 36 with a crank disc 37 fixed on the main shaft 38 of the machine. This main shaft 38 has a worm wheel 39 fixed thereon and meshing with this worm wheel is a worm 40 which is fixed on a driving shaft 41 provided with a belt pulley 42 where through power is transmitted to the machine. The paper from the feed rolls passes over a platform 43 and onto a pair of spaced platforms 44. Between the platform 43 and the spaced platforms 44 is fixed a knife blade 45 mounted on the frame 10 and coacting with this knife blade is a movable knife blade 46 which is swingingly mounted on the frame at the ends of pivoted arms 47. At the driving end of the machine this movable knife blade is connected by a link 48 with a lever 49 pivoted intermediate its ends and operated by means of a cam 50 fixed on the shaft 38 and bearing on a roller 51 carried by said lever 49. A spring 52 holds this lever in contact with said cam.

At 53 is a conveyor support and this support may be located at any desired distance from the machine proper. Carried by the support 53 is a conveyor roll 54 and journaled in the frame 10 is a second conveyor roll 55, the two rolls being connected by a belt 56. On the upper side of the conveyor the belt runs over a platform 57 between laterally adjustable side beds 58 so that different sizes of loaves can be accommodated. The roll 55 is fixed on a shaft 59 and this shaft 59 has fixed thereon a ratchet wheel 60 adjacent to which is a gear wheel 61 carrying a disc 62 supporting pawls 63 coacting with the ratchet 60. Engaging the gear 61 is a rack 64 which is connected by a link or con-

necting rod 65 with a crank disc 66 fixed on the shaft 38. Thus, the rotation of the crank disc imparts a step by step movement to the conveyor.

At 67 is a plunger mounted in guides 68 and carrying on its upper end an elevator table 69. This plunger is actuated by means of a lever 70 slotted as at 71 to engage a pin 72 on the plunger. The lever 70 is pivoted to the frame 10 by means of an arm 73 and its remaining end is connected to the plate 74 of an eccentric 75 fixed on the shaft 38 so that rotation of said shaft alternately raises and lowers the elevator 69. At 76 is an upper frame and between the ends of this frame extend guide bars 77 whereon is mounted a carriage 78 supporting a downwardly extending pivoted folder 80. The carriage 78 is connected by a link 81 with a lever 82 pivoted on the shaft 83 and having its lower end connected by a plate 84, slotted to engage the shaft 38, with a cam 85. Above the carriage 78 are provided trip cams 86 engageable by rollers 87 on arms 88 extending upward from the pivot folder 80. As the bread is lifted by the elevator between the platforms 44 the paper is carried on top of the bread and the loaf passes between the folders 79 and 80 which are adjusted for the size by means of screws 89 and slots 90 so that the sides of the paper are folded down as shown in Figure 9. Slidably mounted on the frame 10 is a carriage 91 supporting the end tuckers 92 and this carriage is reciprocated by a link 93 connected to the upper end of a lever 94 pivoted on the shaft or rod 83 and having its lower end connected to the blade 95 of an eccentric 96 fixed on the shaft 38. Slidably mounted on the carriage 91 is a bottom folder plate 97 which is connected by a link 98 with a lever 99 pivoted on the shaft 83 and having its lower end connected to the blade 100 of an eccentric 101. At the conveyor end of the machine there is a platform 102 having an opening 102a and whereon are supported end folding members or brackets adjustable to and from each other by slots 104 and bolts 105 formed in their supporting brackets. Mounted on these end folding members are tuckers 106. Heating elements 107 are arranged beneath the platform and the ends folding members and these latter have their ends adjacent the elevator curved as shown best in Figure 3 at 108. Extending away from the platform 102 is the delivery conveyor 109 provided with the adjustable side 110.

It is to be noted that each and all of the parts are adjustable to accommodate loaves of different sizes. In the operation of the device it will be seen by referring to the diagrammatical figures that the first step in the operation is the delivery of the loaf on the elevator. The cams and eccentrics

- are so arranged that at the time the loaf is delivered in this position a sheet of paper has been fed forward and cut off. The elevator then rises and the sides of this sheet 5 are folded down by means of the folders 79 and 80. Next the bottom folder 97 advances and folds one side under the loaf, this being shown in Figure 10. Following this movement of the carriage 91 the tucker 92 accomplishes the tucking of the side of the wrapper just acted on by the folder 97 as seen in Figure 11. The carriage 78 then moves so that the paper on the opposite side is folded by the edge of the platform 102 beneath the 10 loaf, continuation of this movement causing the tuckers 106 to fold this remaining side inward and at the same time the releasing cams 86 will act to free the folder 80 from the loaf. As the loaf moves further the 15 curved surfaces 108 engage the bottom and top of the wrapper or paper and fold that respectively up and down thus completing the wrapping. Continuation of movement of the loaf brings the folded bottom and 20 end seams opposite the heater which melts the paraffin, usually employed in such paper, and causes the edges to stick together. From this point the loaf is pushed 25 off to the delivery conveyor.
- Having thus described the invention what is claimed as new, is:
1. In a bread wrapping machine, a wrapping paper holding and feeding mechanism, a loaf elevating mechanism movable to bring a loaf into contact with the paper fed from the first mentioned mechanism, a horizontally reciprocating paper folding and loaf moving device movable to and from a position above the elevating 30 mechanism, reciprocating mechanisms for folding one side of the paper under the loaf and for folding one side of each end inward, means to actuate said mechanisms in timed relation, and stationary devices arranged to act on the paper as the loaf moving device moves away from above the elevating mechanism and arranged to successively fold the remaining side of each end inward on the loaf end and fold the top 35 and bottom portions of the paper ends over the side portions thereof.
  2. In a bread wrapping machine, a wrapping paper holding and feeding mechanism, a loaf elevating mechanism, movable to bring a loaf into contact with the paper fed from the first mentioned mechanism, a horizontally reciprocating paper folding and loaf moving device movable to and from a position above the elevating mechanism, reciprocating mechanisms for folding one 40 side of the paper under the loaf and for folding one side of each end inward, means to actuate said mechanisms in timed relation, stationary devices arranged to act on the paper as the loaf moving device moves
  3. In a bread wrapping machine, a main frame, a supplemental frame above said main frame, a platform on said main frame having an opening adjacent one end, a plunger reciprocably mounted to pass through said opening, a carriage mounted on the supplemental frame to reciprocate 45 across said opening, a folding member fixed to one side of the carriage and depending therefrom, a second folding member pivoted at its upper edge to the other side of said carriage and depending therefrom, means to reciprocate the plunger, means to reciprocate the carriage in timed relation to the plunger, and coacting elements on the supplemental frame and second folding member arranged to swing the second folding member 50 into horizontal position upon movement of the carriage over the platform and away from the opening.
  4. In a bread wrapping machine, a main frame, a supplemental frame above said main frame, a platform on said main frame having an opening adjacent one end, a plunger reciprocably mounted to pass through said opening, a carriage mounted on the supplemental frame to reciprocate 55 across said opening, a folding member fixed to one side of the carriage and depending therefrom, a second folding member pivoted at its upper edge to the other side of said carriage and depending therefrom, means to reciprocate the plunger, means to reciprocate the carriage in timed relation to the plunger, arms projecting upward from the second folding member, rollers on the upper end of said arms, fixed cam members 60 on the supplemental frame engaging said rollers to swing the second folding member into horizontal position upon movement of the carriage over the platform and away from the opening, and spring means holding said rollers in engagement with said cams.
  5. In a bread wrapping machine, a main frame, a supplemental frame above said main frame, a platform on said main frame 65 having an opening adjacent one end, a plunger reciprocably mounted to pass through said opening, a carriage mounted on the supplemental frame to reciprocate across said opening, a folding member fixed to one side of the carriage and depending therefrom, a second folding member pivoted at its upper edge to the other side of said carriage and depending therefrom, means to reciprocate the plunger, means to reciprocate 70 the carriage in timed relation to the plunger, arms projecting upward from the second folding member, rollers on the upper end of said arms, fixed cam members on the supplemental frame engaging said rollers to swing the second folding member into horizontal position upon movement of the carriage over the platform and away from the opening, and spring means holding said rollers in engagement with said cams.

cate the carriage in timed relation to the plunger, arms projecting upward from the second folding member, rollers on the upper end of said arms, fixed cam members on the supplemental frame engaging said rollers to swing the second folding member into horizontal position upon movement of the carriage over the platform and away from the opening, spring means holding said rollers in engagement with said cams, and stops on said carriage limiting the movement of the second folding member toward the first.

6. In a machine of the class described, a platform having an opening therein where-
15 through the loaf to be wrapped may rise, means to raise the loaf through said opening, a bread holder above said platform and adapted to move to and from position of said opening, a carriage mounted on said 20 platform and reciprocating longitudinally thereof over and away from said opening, end tuckers mounted on said carriage and moving therewith, a bottom folder slidably mounted on said carriage, and means to 25 move the carriage and bottom folder in timed relation.

7. In a machine of the class described, a platform having an opening therein, guides extending longitudinally of the platform 30 across and above said opening, a carriage slidably mounted on said guides, folders mounted for lateral movement with respect to said carriage, means to hold said folders in laterally adjusted relation, end tuckers 35 mounted on said folders, means to hold said end tuckers in position on the folders, and means to reciprocate said carriage.

8. In a machine of the class described, a platform having an opening therein, guides 40 extending longitudinally of the platform across and above said opening, a carriage slidably mounted on said guides, folders mounted for lateral movement with respect to said carriage, means to hold said folders in laterally adjusted relation, end tuckers 45 mounted on said folders, guides extending longitudinally of said carriage and fixed thereon, a bottom folder slidably mounted in said last guides, and means to reciprocate said carriage and bottom folder in timed relation.

9. In a machine of the class described, a platform having an opening therein, an elevator for moving a bread loaf upward 50 through said opening, a frame mounted on said platform and extending above the same, a pair of guide rods extending longitudinally of the frame in spaced relation above the platform, a carriage slidable on said guide rods, folders adjustable longitudinally of said carriage, means to hold said folders in longitudinally adjusted position, a fixed

folding member secured to one side of said carriage and rigid therewith, a folding member pivoted to the other side of the carriage and movable from vertical loaf engaging position to horizontal loaf freeing position, means to reciprocate said carriage and means to move the second mentioned folding member on its pivot.

10. In a machine of the class described, a platform having an opening therein, an elevator for moving a bread loaf upward through said opening, a frame mounted on said platform and extending above the same, a pair of guide rods extending longitudinally of the frame in spaced relation above the platform, a carriage slidable on said guide rods, folders adjustable longitudinally of said carriage, means to hold said folders in longitudinally adjusted position, a fixed folding member secured to certain of said folders and rigid therewith, a folding member pivoted to the remaining bracket and movable from vertical loaf engaging position to horizontal loaf freeing position, means to reciprocate said carriage and means to move the second mentioned folding member on its pivot, comprising arms projecting upward from said folding member, rollers carried by said arms, and cams on said frame engaging said rollers.

11. In a machine of the class described, a platform having an opening therein, means to move a partly wrapped loaf longitudinally of said platform, a pair of guide members, brackets supporting said guide members and adjustably secured to said platform, said guide members being movable toward and from each other to accommodate loaves of varying lengths, means to hold said brackets in adjusted relation and trucker members mounted on said guide members and projecting in the path of the partly wrapped loaf.

12. In a machine of the class described, a platform having an opening therein, means to move a partly wrapped loaf longitudinally of said platform, a pair of guide members, brackets supporting said guide members and adjustably secured to said platform, said guide members being movable toward and from each other to accommodate loaves of varying lengths, means to hold said brackets in adjusted relation, tucker members mounted on said guide members, and projecting in the path of the partly wrapped loaf, the said guide members having their ends adjacent the tucker members curved to engage the lower and upper parts of the projecting portion of the wrapper on the loaf.

In testimony whereof I affix my signature.
HENRY WATERSTONE.
